-et al.

UNITED STATES PATENT OFFICE.

ALEX WENDELBURG, OF NEW YORK, N. Y., ASSIGNOR TO PITTSBURGH ELECTRIC TOOL COMPANY, OF NEW YORK, N. Y., A CORPORATION OF PENNSYLVANIA.

ELECTRIC-HAMMER SWITCH

1,250,402.

Specification of Letters Patent. Patented Dec. 18, 1917.

Original application filed July 28, 1914, Serial No. 853,784. Divided and this application filed April 28, 1915, Serial No. 24,547. Renewed September 20, 1917. Serial No. 192,413.

To all whom it may concern:

Be it known that I, ALEX WENDELBURG, a citizen of the United States, residing in the city, county, and State of New York, have 5 invented certain new and useful Improvements in Electric-Hammer Switches, (division of application Ser. No. 853,784, filed July 28, 1914;) and I do hereby declare the following to be a full, clear, and exact description of the invention, such as will enable others skilled in the art to which it appertains to make and use the same.

This invention relates to electric hammers adapted for use in chipping, calking, riveting, cutting and other work requiring a rapid succession of blows upon a suitable tool. The invention is directed to an improved form of electric hammer which is simple in construction, which may be manufactured at low cost, which is so constructed as to permit of cooling by immersion in a liquid, which is of comparatively light weight and which possesses such strength and rigidity as will enable it to withstand 25 the continual jarring to which it is subjected in use.

The invention herein claimed involves the provision of an improved form of circuit-controlling mechanism whereby the operation 30 of the hammer is governed. This involves the provision of a cavity in the handle of the hammer in which a circuit-breaker of special form is removably mounted, this circuit-breaker being operable to open and close the circuit to the coils of the hammer. The construction of the circuit-breaker is such as to insure a good contact when the operating handle of the switch is moved to the closed position and to minimize the danger 40 of arcing at the terminals by the provision of auxiliary contact surfaces which effect a delayed breaking of the circuit.

The invention also involves numerous other features of improvement in the construction of the hammer whereby great strength, good wearing qualities and ample protection of the parts are obtained. These and other features of the invention will be better understood by reference to the following description taken in connection with the accompanying drawing which shows the preferred embodiment of the invention herein claimed.

In the drawing, Figure 1 is a central sec-

tional view of a hammer embodying my invention;

Fig. 2 is an enlarged sectional view through the circuit-controlling mechanism;

Fig. 3 is a transverse section of the circuit-controller on line 3—3 of Fig. 2; and

Fig. 4 is a diagram of the circuit connections.

Referring to these drawings, the frame of the hammer consists primarily of a tubular casting 4 and a handle casting 5. The casting 4 is of non-magnetic material, preferably phosphor bronze, and the tubular passage therethrough contains a reciprocating solenoid core or plunger 6, adapted to strike the end of a tool to be inserted through the hollow tool-guide 14, hereinafter mentioned. The casting 4 is provided with radially disposed walls 7, 8 and 9, which provide spaces between them for solenoid coils 10 and 11. These coils are wound in opposite directions and serve to develop magnetic fields which actuate the plunger 6 constituting the core of the solenoid. The coils are inclosed by a casing 12 which is preferably a piece of steel tubing. This tubing and the walls 7, 8 and 9, are of such dimensions that the tubing fits snugly around the walls, and the spaces between the walls, 7, 8 and 9, and the casing 12 are completely filled by the coils 10 and 11. The forward ends of the casting 4 and the casing 12 are connected together by a nozzle 13. For this purpose, the projecting end of the casting 4 is provided with an exterior thread with which the nozzle 13 coacts and the nozzle is formed with a projecting flange adapted to fit tightly over the end of the casing 12, as shown. The forward end of the hammer is provided with a tool-guide 14 of slightly smaller internal diameter, so that the plunger cannot slip out. This tool-guide is preferably formed to fit into the end of the casting 4 and have threaded engagement with the end of the nozzle 13. By this construction, the forward ends of the casting 4 and the casing 12 are rigidly connected by the nozzle 13 so as to preclude relative movement of these parts, and the nozzle effects such a tight fit with the guide and casing as will preclude the entrance of a liquid between these parts when the forward end of the tool is immersed, in use, as for purposes of cooling.

At the opposite end of the hammer, the

central passageway through the casting 4 is provided with an enlargement for a cushioning spring 16 to receive the blow of an impact block 15. A portion of this block 15 lies within the tubular passage through the casting 4 in which the striking plunger 6 reciprocates. The remainder of the block 15 is of larger diameter and lies within the enlargement of the tubular passage. The 10 coiled spring 16 bears at one end upon the block 15, the latter being provided with a peripheral flange 17 encircling the end of the spring so as to hold the latter against lateral movement. Between the larger portion 15 of the block 15 and the wall at the end of the enlarged chamber is a washer 18 of tool steel which receives the blow of the block 15 when the latter is returned by the spring 16. The opposite end of the enlarged chamber 20 is closed by a cap 19 which has threaded engagement with the wall of the casting 4. The exteriorly threaded flange on this cap serves as a retainer coacting with the end of spring 16 to hold the latter in position. This 25 flange and the similar flange 17 on block 15 prevent side motion of the spring so that chafing of the spring upon the walls of its inclosing chamber and consequent lack of uniformity in the action of the spring are 30 prevented.

The casting for the handle 5 has a central opening therethrough in which the rear ends of the casting 4 and the casing 12 are received. For securing these parts together, 35 the casing 12 may conveniently have a sleeve 20 secured thereon by means of rivets and forming a circumferential flange. The end 21 of the handle casting 5 closely incloses the end of the casing 12 and is exteriorly threaded to coact with a ring or collar 22 on which is a lip 23 adapted to engage the flange 20. When the sleeve 22 is screwed up tightly, the end 21 of the handle casting and the lip 23, both of which 40 closely inclose the casing 12, engage the flange 20 on opposite sides thereof and grip the handle casting 5 to the casing 12. The casting 5 is also interiorly threaded to coact with a threaded plug 24 which fits closely 45 around the adjacent end of the casting 4, its end abutting against a flange 25 thereon. In this way, both the casing 12 and the casting 4 are connected to the handle casting 5 and these connections are such tight ones 50 that they not only afford the necessary degree of strength, but also preclude the passage of water through them.

The plug 24 is provided with a hole through the center thereof as are also the 55 caps 19 and 15. Because of this provision, air may pass freely from the space between the block 15 and the striking plunger 6 as may also any water which enters this space. The plunger 6 is preferably provided with a 60 radial slot from end to end as is shown for

guarding against the flow of eddy currents in the core of plunger 6.

The flow of current in the coils of the solenoid is controlled by a switch or circuit-breaker located in a cylindrical cavity 70 formed in the handle casting 5 directly above the grip 55 of the handle where the operator may readily press the button of the circuit-controller with his thumb. The parts of this circuit-controller are located within 75 a tube of insulating material and may all be assembled within this tube before the latter is inserted in its cavity within the handle casting. Also, the parts of this circuit-controller are especially constructed so as to 80 provide for a hard rubbing engagement of the contacting surfaces and a delayed break of the circuit at auxiliary contacts. The construction of the circuit-controlling apparatus is shown more clearly in Fig. 2. In 85 the bottom of the cavity in the handle casting 5 are a washer 26 and block 27 of insulating material both of which are removably held in place by a screw 50, as shown in dotted lines in Fig. 2. In the insulating block 27 are two contacts 28, which have wires connected thereto which pass through a passage 29 formed in the casting 5 and are connected to terminals upon a block 30 of insulating material which is secured upon 90 the casting 4 in the space between the latter and the end of the casing 12. The contacts 28 are adapted to be engaged by the ends of pins 31 located in a cylindrical block 32 of insulating material which is secured in the 100 end of a tube 33 of insulating material of a size adapted to fit snugly within the cavity formed in the casting 5. This block 32 is secured to the tube 33 by one or more pins 34. The opposite ends of the pins 31 are 105 threaded into contacts 35 which are of semi-circular form and are secured upon the block 32 directly opposite each other. The ends of these contacts 35 rising from the block 32 are spaced apart and on their adjacent sides they are provided with inclined curved depressions as shown at 36. (Fig. 3).

A second block 37 of insulating material is secured in position within the tube 33 and forms a guide for a movable contact carrier 115 38. This carrier has the contact 39 secured thereon, this contact being in the form of a cup or bell the skirt of which is slotted so as to form a plurality of resilient contact fingers. The contact carrier 38 has a cavity 120 formed therein which receives a spring 42 bearing upon a washer of heat-insulating material resting on the enlarged end 43 of a short rod 44 carrying an auxiliary contact 45. This auxiliary contact is of conical 125 form as shown. The rod 44 is adapted to slide in the opening provided for its reception in the contact carrier 38. The spring 42, being inclosed in a chamber whose walls are of heat-insulating material, is corre- 130

spondingly protected against loss of temper due to the heat of sparking at the contacts when the current is broken; a spring 41 is interposed between the block 37 and a flange 40 of the stem 53 of insulating material having at its top a press button 46. When the parts of the circuit-controller have been assembled within the tube 33 of insulating material, the latter is moved into the cavity in the handle 5 and the end of that cavity is inclosed by a threaded cap 47.

The wires for carrying current to and from the hammer enter the structure through a passage 48 provided in the handle casting 5. A connection block 49 of insulating material carrying three terminals insulated from each other is preferably provided upon the casting 5, at this point, to which block the wires leading to the hammer 20 are connected.

The wiring for carrying current to and from the hammer is illustrated diagrammatically in Fig. 4. By reference to Fig. 4, it will be noted that two of the wires or conductors pass from terminals on the insulating block 49 to the block of insulating material 30, and, from said block 30 are continued by other wires until they are connected respectively to the non-adjacent ends of 30 the coils 10 and 11. The adjacent ends of these coils are connected together, and, from their point of connection, a wire leads to the block 30, and is continued by another wire from the block 30 to one of the contacts 28. From the other contact 28, a wire leads to the third terminal upon the insulating block 49. These connections are such that the connection from the junction of the two coils 10 and 11 to the other side of the 40 circuit may be opened or closed by the circuit-breaking mechanism located in the cavity of the handle, since this connection is made through the contacts 35 which are connected or disconnected by the bell 39 and auxiliary contact 45. In Fig. 4, the insulating block 30 is shown as provided with individual grooves for the reception of the several wires or conductors referred to. In assembling and disassembling the hammer, 50 the wires leading from the insulating block 49 and from one of the contacts 28 to the insulating block 30 can be electrically connected with the continuations of those wires respectively by means of suitable connecting 55 and disconnecting screws 56, as will be readily understood.

When the button 46 is pressed, the contact 39 and auxiliary contact 45 are moved forward and the latter engages the inclined surface 60 faces 36 upon the contacts 35, so closing the circuit. As the movement of button 46 is continued, the auxiliary contact 45 is moved back, relative to the contact carrier 38 thereby compressing the spring 42. As this takes 65 place, the contact 39 moves over the contacts

35 so as to effect an electrical connection between them. By reason of the resiliency of the slotted skirt of the bell-shaped contact 39, a good rubbing engagement of the contact 39 upon the contacts 35 is obtained. Furthermore, the conical form of the auxiliary contact 45 causes the contacts 35 to spread somewhat so that they are forced apart and therefore effect a more intimate engagement with the contact 39. When the pressure on the button 46 is relieved, the spring 41 forces the contact carrier 38 and the contact 39 upwardly so as to interrupt the connection of the contacts 35 by the contact 39. While this is taking place, however, the auxiliary contact 45 does not immediately disengage the contacts 35 for the reason that it is still kept in contact with them momentarily by the spring 42. After the contact 39 has moved away, however, a distance sufficient to clear contacts 35, the contact 45 disengages these contacts so as to break the circuit. As a consequence, whatever arcing there is takes place between the contact 45 and the surfaces 36, and has no effect upon the surfaces of contact between the slit bell 39 and the outer peripheries of the contacts 35, which therefore remain constantly bright and in efficient conductive condition.

The circuit-breaker herein described may be readily constructed at low cost by assembling the parts within the insulating tube 33 and thereafter inserting that tube in the cavity in the handle of the hammer. In 100 operation, this circuit-controller serves to close and open the circuit effectively, a good contact of large surface area being insured by the arrangement of the contact 39 to inclose the two contacts 35 and the contact 45 to spread the contacts 35 into hard engagement with the contact 39.

It will be noted that the construction of the hammer is such as will permit of cooling it by inserting the whole of the forward portion of the hammer in a cooling liquid. The coils 10 and 11 are so inclosed and the connections between the inclosing parts are such that the entrance of the cooling liquid into the chambers for the coils is precluded.

To further insure this result, the flange 57 is brazed to the shell or casing 12, and a thin asbestos gasket 58 is inserted at the point indicated; in addition to which the screw-threads connecting the nozzle 13 to the end of the casting 4 and to the tool-guide 14 may be shellacked before assembling the parts, thereby making absolutely water-tight joints.

Furthermore, the parts of the hammer are connected together with such strength and rigidity that the continual and severe jar-ring incident to the use of the hammer will not cause the parts to work loose. The tool steel washer 18 which receives the return 130

blow of the block 15 is fixed in position within its cavity, preferably by shrinking it in place, in order that it may not follow the upward movement of said block.

5 I claim:

1. In an electric hammer, the combination of a pair of yielding contacts, a plunger, a slotted bell carried by said plunger and movable to embrace and bridge said contacts, and means for spreading said contacts against the inner face of said bell.

2. In an electric hammer, the combination of a pair of yielding contacts, a spring-pressed plunger, a metal bell carried by said 15 plunger and movable therewith to embrace and bridge said yielding contacts, and a wedge-shaped conductor adapted to enter between and spread said yielding contacts, substantially as described.

20 3. In an electric hammer, the combination of a pair of yielding contacts, a spring-pressed plunger, a slotted metal bell carried by said plunger and movable to envelop and bridge said yielding contacts, and 25 an auxiliary contact member yieldingly mounted on said plunger and adapted to enter between and bridge said yielding contacts.

4. In an electric hammer, the combination 30 of a pair of yielding contact members, a sliding spring-pressed plunger, a conductive element carried by said plunger and adapted to engage the outer faces of said contact members and form a bridge between said 35 members, and a spring-pressed rod mounted in said plunger and adapted to enter between said contact members and spread the same against the inner face of said element, said rod being slidably mounted and projecting from said plunger far enough to give a delayed break when said plunger moves its conductive element out of engagement with said contact members.

5. In a hammer handle, a digitally operated plunger, a bridging conductor carried by said plunger, a pair of contacts to be bridged thereby, a spring-pressed rod slidably mounted in said plunger, said rod having an auxiliary tapering contact adapted 50 to enter between said first-named contacts before their engagement with the bridging conductor, said auxiliary contact giving a delayed break for current between said bridged contacts when said plunger is withdrawn.

6. An electric hammer handle having a cavity, a pair of contacts located therein, a member movable in said cavity and carrying a conductor adapted to inclose and yieldingly embrace said pair of contacts, an auxiliary contact member slidably mounted in said movable member and adapted to enter between said pair of contacts and electrically connect the same when said member 65 moves inward, and a spring permitting rela-

tive movement of said auxiliary contact member to delay the interruption of the circuit between said first-named pair of contacts when said movable member moves outward, substantially as described.

7. In an electric hammer, a handle having a cavity therein, a tube of insulating material in said cavity, a pair of contacts located in said tube, a movable member having a contact of circular form located thereon 75 adapted to engage and connect said contacts, and a movable spring-actuated contact upon said movable member adapted to enter between said contacts and spread the same, substantially as described.

8. In an electric hammer, a handle having a cavity therein, a pair of contacts fixed at the base of said cavity, a tube of insulating material removably mounted in said cavity, a pair of contacts located in said 85 tube and adapted to be detachably connected with said first-mentioned pair of contacts, a digitally operated member movable in said tube and carrying a contact adapted to inclose and yieldingly embrace said pair of 90 contacts in said tube, an auxiliary contact member slidably mounted in said movable member and adapted to enter between said pair of contacts in said tube when said member moves inward, and a spring permitting 95 relative movement of said auxiliary contact member to delay the interruption of the circuit when said movable member moves outward; substantially as described.

9. In an electric hammer, a handle having a cavity therein, a tube of insulating material in said cavity, a pair of yielding contacts located in said tube, a digitally operated plunger movable in said tube and carrying a slotted bell adapted to inclose and 105 yieldingly embrace said pair of contacts, said plunger being provided with a chamber, a spring in said chamber, and an auxiliary contact member engaged by said spring and slidably mounted in said plunger, 110 said auxiliary contact member being adapted to enter between said pair of contacts and spread the same against the inner face of the bell when the plunger moves inward and giving a delayed break for current between the pair of contacts when said plunger moves outward.

10. In an electric hammer, a handle having a cavity therein, a pair of contacts located in said cavity, each of said contacts 120 being of semi-circular outline, a digitally operated plunger movable in said cavity and carrying a slotted bell adapted to inclose and yieldingly embrace said pair of contacts, said plunger being provided with a chamber 125 inclosing a spring, and an auxiliary contact member slidably mounted in said plunger and adapted to enter between said pair of contacts and electrically bridge the gap therebetween when the plunger moves in- 130

- ward and before said bell reaches said contacts, the spring within said plunger permitting relative movement between said auxiliary contact and said slotted bell, and giving a delayed break for current between said pair of contacts when said plunger moves outward in said cavity.
11. In an electric hammer, a handle having a cavity therein, a tube of insulating material in said cavity, a pair of contacts located in said tube, a movable member having a contact located thereon adapted to engage and connect said contacts and a movable spring-actuated contact upon said mov-
- able member adapted to enter between said contacts.
12. In an electric hammer, a handle having a cavity therein, a tube of insulating material in said cavity, a pair of contacts located in said tube, a movable member having a contact located thereon adapted to engage and connect said contacts and a movable spring-actuated contact upon said movable member adapted to enter between said contacts and spread the same.

In testimony whereof I affix my signature.

ALEX WENDELBURG.
